US00D648082S

(12) **United States Design Patent**
Alexander et al.

(10) **Patent No.:** US D648,082 S
(45) **Date of Patent:** ** Nov. 1, 2011

(54) **PRESSURE WASHER**

(75) Inventors: **Gus Alexander**, Inverness, IL (US);
Ryan D Sherwood, Chicago, IL (US);
Christopher C Alexander, Chicago, IL (US); **William N Alexander**, Inverness, IL (US)

(73) Assignee: **FNA IP Holdings, Inc.**, Elk Grove Village, IL (US)

(**) Term: **14 Years**

(21) Appl. No.: **29/392,168**

(22) Filed: **May 18, 2011**

Related U.S. Application Data

(62) Division of application No. 29/365,617, filed on Jul. 12, 2010, now Pat. No. Des. 639,001.
